UNITED STATES PATENT OFFICE.

CHARLES H. BAILEY, OF IRVING, ILLINOIS.

PORTABLE RAILWAY-CROSSING.

1,131,457.

Specification of Letters Patent.

Patented Mar. 9, 1915.

Application filed July 16, 1914. Serial No. 851,325.

To all whom it may concern:

Be it known that I, CHARLES H. BAILEY, a citizen of the United States of America, residing at Irving, in the county of Montgomery and State of Illinois, have invented certain new and useful Improvements in Portable Railway-Crossings, of which the following is a specification.

This invention relates to railway crossings and, more particularly, to a track level crossing intended for the use of pedestrians.

The objects of the invention are: to provide a crossing of simple, cheap, and durable construction; to provide a crossing which may be assembled at the work shops and easily transported to the desired points and quickly put in place.

With these and such other objects in view, as may hereinafter more fully appear, my invention consists in the novel arrangement and construction of parts set forth in the following description, more particularly pointed out in the claims, and which are shown in the accompanying drawings, wherein:

Figure 1 is a plan view of a section of railway track with my crossing in place thereon. Fig. 2 is a transverse vertical sectional view of the same. Fig. 3 is a prospective view of a section of the crossing. Fig. 4 is a detail broken sectional view taken on the line 4—4 of Fig. 3.

Referring to said drawings by numerals: Longitudinal side members, of any suitable material, but preferably of metal, are provided with end extensions 1 suitably apertured, as at 2, for the reception of nails or spikes 3, for the purpose of securing the same to the ties 4. These side members are formed with the upright portions 6, to form sides of the frame, and a lower inturned portion 7, adapted to form a base for the crossing. The upper angularly disposed edges 8 of said side members are adapted to overlie the upper surface of the material of said crossing and form a guard for the edges thereof. Angled end pieces 9 are

transversely disposed between the side pieces and are secured to the portion 7 thereof by means of rivets 5. Within the frame work thus formed is placed cement 10 or other suitable material to form a crossing. The sections of the crossing positioned on the outside of the rails, are made sloping as shown most clearly in Fig. 2, and the retaining frame is preferably formed of one sheet of metal 11 bent to a suitable form for retaining the cement 10.

As will be readily understood, the frame work may be assembled and the cement filling placed therein at any convenient place and the sections of the crossing taken to the desired points and quickly put in place, when needed.

Having described my invention, what I claim as new, and desire to secure by Letters Patent, is:

1. In a portable railway crossing, angular side members, angular end members secured transversely of said side members, a cement filler retained by said side and end members, and means for securing said crossing to the ties.

2. In a portable railway crossing, a frame comprising, angular side members, an angularly disposed upper edge on said side members, angular end members secured transversely of said side members, and a cement filler within said frame.

3. In a portable railway crossing, a frame comprising, side members, inwardly projecting angularly disposed base portions on said side members, angularly disposed edge protecting portions on the upper edge of said side members, end retaining members secured transversely of said side members, a cement filler within said frame, and means for securing said frame to the ties.

In testimony whereof I hereunto affix my signature in presence of two witnesses.

CHARLES H. BAILEY.
